UNITED STATES PATENT OFFICE.

FREDERICK W. GROBY, OF NEW YORK, N. Y.

DRAFTING-MACHINE.

1,185,996.

Specification of Letters Patent.

Patented June 6, 1916.

Application filed March 17, 1908. Serial No. 421,743.

To all whom it may concern:

Be it known that I, FREDERICK W. GROBY, a citizen of the United States, residing at New York, in the county of New York and 5 State of New York, have invented certain new and useful Improvements in Drafting-Machines, of which the following is a specification.

The principal object of my said invention 10 is to provide a machine capable of being manipulated to draw lines at any angle desired and one by which the length, angle and position of the lines and their distance apart may be accurately determined without 15 the aid of other instruments, and further to adapt said invention for use in connection with mechanism by which notations of desired information may be made adjacent to the lines during the progress of the 20 work, all as will be hereinafter more fully described and claimed.

Referring to the accompanying drawings which are made a part hereof and on which similar reference characters indicate similar parts, Figure 1 is a top or plan view of 25 a machine embodying my said invention, Fig. 2 a side elevation of the same, and Figs. 3, 4, 5 and 6 detail views illustrating 30 features of construction on an enlarged scale.

In said drawings the portions marked A represent the bed upon which the machine is mounted, B the base of the frame on 35 which the movable marking machine is supported, and C the base of the frame of said movable machine.

In the drawings I have illustrated my invention in connection with a book-typewriter of ordinary construction, which construction, 40 as well as its operation, is, in the main, so far as its ordinary functions are concerned, substantially of the well-known character, and needs no special description herein.

45 The base A may be any suitable table or base on which the work is to be done, a flat platen being mounted thereon for holding said work. Said base is provided with a standard A' near its rear edge in the top 50 of which is formed a central bearing for the pivot a of a top or head portion A² which is thus pivotally mounted thereon, being held from rotation by a set-screw a², or other suitable locking means. Said standard 55 is preferably mounted so as to be adjusted transversely across said base by

means of a screw-rod B⁸ mounted in bearings on said base and engaging with a screw-threaded perforation in a shank b⁸ on the bottom of said standard which extends into a transverse slot in said base. A hand-wheel b⁹ is provided on said screw-rod for operating it. The standard may be locked securely in any position by clamping bolts b¹⁰. 60

The frame B is of rectangular form and of a size and material suitable for the purpose, provided with uprights B' at each corner, the tops of which are connected by a spider-like frame B² one bar of which extends from the top of each standard to a central hub B³ having an upwardly projecting pintle b³. Said hub B³ is pivoted to the inner end of a horizontal arm B⁴, as shown most plainly in Fig. 6. The outer 70 end of said arm B⁴ is rigidly mounted in the top of the pivoted head A². A spring latch b is mounted on the side of said hub B³ and is adapted to engage with any one of a series of notches b' formed around the 80 periphery of a downwardly projecting cylindrical part on the inner end of arm B⁴ in positions to mark degrees of a circle. By means of said latch b the frame B may be held at any angle in relation to said arm 85 B⁴. Mounted to extend longitudinally of the frame B are toothed rack-bars B⁵ constituting tracks on which the machine proper may run, being of the usual or any preferred 90 arrangement.

The machine frame C may be the frame of any book-typewriter or a frame especially designed for the purpose, being shown only to illustrate the use of my said invention. It is mounted to travel on the tracks B⁵, being actuated by the usual, or any preferred, mechanism. On said frame C are mounted the adding devices C⁸ and the carriage C', adapted to travel on the ways 20 provided therefor, transversely to the travel 100 of the frame C on the tracks B⁵. Said carriage C' carries the usual typewriting mechanism and the operating mechanisms therefor, all of which are or may be of any well-known or approved construction and need 105 no special description herein. On said carriage C' I have mounted a marker c which may be a pencil, pen, perforating wheel or any other marking implement desired, adapted to be adjusted into or out of contact with the surface of the work. In Figs. 3 and 4 I have illustrated said marker as 110

mounted in a socket 1 mounted on a bar 2 which bar is pivoted to a piece c' on the lower part of the carriage C' and at its outer end is hinged to an upright rod 3 which is 5 pivoted at its outer end to a horizontal bar 4 pivoted at an intermediate point in the top of a standard c^2 of another part of said carriage C' , the other end of said bar 4 being pivoted to a key 5, which is preferably located in the keyboard of the typewriter. In 10 Fig. 3 the normal position of the marker is shown, being held up out of contact with the work by means of a weight 6. In Fig. 4 the marker is shown in position for marking upon the surface of the work, the key 5 being forced down, which operates through the connecting parts to change the position, as shown. In Fig. 5 I have shown the socket 1 as mounted in a fixed position on the end 15 of a part 7 of the frame. A set-screw 9 in the side of said socket enables said marker to be adjusted up and down into and out of contact with the work.

It will be understood, of course, that the 25 manner of mounting or the particular location of the marker is immaterial to the object of my said invention, and that said marker may be mounted in any suitable manner and operated into and out of contact with the work by any suitable mechanism. It being mounted upon the carriage C' which slides transversely of the frame C and said frame being adapted to travel longitudinally upon the tracks B^5 , it will be 30 seen that said marker can be made to draw lines back and forth across the work and also that as said frame C is capable of being moved in one direction across the work regular spaces or distances by the feeding 35 mechanism forming part of the ordinary typewriter construction, the lines may be made at any distance apart desired. Stops c^4 are provided for insertion in a series of holes in a bar 21 of the frame C alongside 40 of the way for carriage C' , and are adapted to be inserted in the appropriate hole to limit the movement of said carriage at any points desired. A scale C^3 is mounted to 45 extend from side to side of the machine and an indicator on the end of an arm 8 is carried on a part of the frame adjacent to said scale, so that any distance desired may be 50 readily determined upon the work. The carriage C' is connected by flexible connections 55 c^5 and c^6 with spring controlled spools or "power-barrels" C^5 and C^6 for sliding said carriage in one direction on the frame step by step, as the feeding mechanism is operated, in the same manner as in an ordinary 60 book-typewriter construction.

It will thus be seen, that, by releasing the feed mechanism which controls the sliding of carriage C' in one direction upon the frame C , the carriage will be drawn automatically across the ways on the top of

frame C and that the marker carried on said carriage will describe accurate lines and can be controlled by the stops and indicating mechanism so that the lines drawn will be in the exact location desired and of the proper length. After feeding said frame by the feed mechanism to the limit desired in one direction across the work it may be manually returned on the track in the same manner as in the common typewriter construction. By releasing the spring catch b the frame B carrying the machine can be turned so that the carriage C' may be caused to travel at any angle desired across the work W , and thus draw lines at any angle to a given line. By the use of the typewriter any numerals, characters or wording desired alongside the lines can be readily applied and by the use of the adding machine attachment various computations can be readily made upon the work, such as tabulating, billing and work of a like character, in which work all of the ruling necessary can be rapidly and quickly done by the marking device, as will be readily understood. By means of the screw-rod B^8 the standard A' carrying the entire apparatus may be moved transversely of the bed or table A , and the machine thus enabled to do work of any length desired without requiring a carriage of undue length. By loosening set-screw a^2 the entire frame B , carrying all the mechanism, may be swung around on the arm B^4 to one side of platen P to be out of the way when it is desired to adjust the work in the platen, or have access to said work for any purpose.

It will be understood, of course, that the details of construction and arrangement may be varied as found desirable, the typewriting and computing mechanism used or not according to the requirements of the work, and other modifications made without departing from my invention as defined in the claims.

Having thus fully described my said invention, what I claim as new and desire to secure by Letters Patent, is,

1. In an apparatus for drawing lines, the combination of a work supporting table, a support on said table, a frame provided with tracks and pivotally mounted on said support above said table, a frame mounted to travel on said tracks, a carriage mounted to reciprocate on said frame at right-angles to its movement on said tracks, and a marker adapted to slide on the surface of the work mounted on said carriage, substantially as set forth.

2. In an apparatus for drawing lines, the combination, of a table, a support on said table, a frame mounted on said support on a vertical pivot above the table, a track carried by said frame, a reciprocable frame on said track, a carriage on said reciprocable

frame, and a marker mounted on said carriage, substantially as set forth.

3. In an apparatus for drawing lines, the combination, of a table, a support on said table, a frame mounted on said support to pivot horizontally above said table and provided with tracks, another frame mounted to run on said tracks longitudinally of said first named pivoted frame, a carriage mounted to traverse across said last named frame, and a marker mounted on said carriage, substantially as set forth.

4. A drafting apparatus comprising a table, a support on said table, a frame mounted on said support above the table on a vertical pivot, a second frame adapted to move longitudinally on said pivoted frame, a carriage mounted to move transversely on said second frame, a marker on said carriage for drawing lines, and writing mechanism also mounted on said carriage, whereby information may be inscribed alongside of the lines made by the marker, substantially as set forth.

5. A drafting apparatus comprising a table for supporting the work, a support on said table, a frame pivoted on said support on a vertical pivot above the table and movable lengthwise of the table, a transversely movable carriage on said frame, a marker on said carriage adapted to slide on the surface of the work for drawing lines, and typewriting mechanism also on said carriage for inscribing information alongside said lines, substantially as set forth.

6. In a drafting apparatus, the combination, of a table, a support mounted on

said table to be adjusted transversely thereof, a frame carried by said support above the work, and a machine mounted to move longitudinally on said frame comprising a transversely movable carriage carrying a marker adapted to slide on the surface of the work for drawing lines, substantially as set forth.

7. In a drafting apparatus, the combination of a support, a frame pivoted on a vertical pivot on said support, a carriage, means for mounting said carriage on said frame to move longitudinally and transversely of said frame, and a marker on said carriage for drawing lines, substantially as set forth.

8. A drafting apparatus comprising a table, a support on said table, a frame pivoted on a vertical pivot on said support and above the table, a marker, writing mechanism, and means on said frame for mounting the marker and mechanism to slide longitudinally and transversely of said frame, substantially as set forth.

9. In an apparatus for drawing lines, the combination of drafting and typewriting mechanisms, a support, and means for pivotally mounting said mechanisms on a vertical pivot on said support, substantially as set forth.

In witness whereof, I have hereunto set my hand and seal at Washington, D. C., this 16th day of March, A. D. nineteen hundred and eight.

FREDERICK W. GROBY. [L.S.]
